MINE WALLING

Joseph Parusel, Gleiwitz, Germany

No Drawing. Application July 7, 1934, Serial No.
734,195. In Germany June 28, 1932

2 Claims. (Cl. 61—45)

This invention relates to a yielding lining or walling for mines. Up to now timber insertions have been used for this purpose but these are 5 comparatively expensive and have only a short life.

It is known that tar beton (tar concrete) used in constructing roads has great yielding capacity. The invention utilizes this property of tar beton 10 for the walling of mines.

The mine walling according to my invention is composed of preshaped bricks, or blocks, of tar beton.

These bricks may be made from tar beton by 15 moulding a mixture of tar and other material adapted to make beton under pressure in the hot or cold state. Such bricks possess various resistances against pressure depending on the method of their manufacture. Particularly, the 20 yielding capacity of shaped pieces of tar beton is regulated by suitable choice of the binder (tar), its hardness and the size of the stony particles combined thereby. Tar beton bricks of greater strength are used for the main part of the wall- 25 ing or lining, whilst bricks of smaller strength are used as insertions (fillers) in the gaps between the bricks of greater strength, instead of the known timber insertions. In order to increase the strength of the bricks they may be 30 armoured by iron.

Linings, composed of blocks or bricks, accord-

ing to the invention, are practically not attackable by moisture, particularly by earth and mountain water containing acids and salts. Such blocks, or bricks, of uniform and homogeneous 5 structure are easily and cheaply made above the ground and mounted below the ground in the mine at low cost, because no re-enforcements are necessary like heavy and difficultly fitted iron structures. A lining composed according to the 10 invention has therefore proven superior to known linings composed of concrete, iron and wood as to stability against chemical attacks and cor- 15 sions. The lining yields to pressure without ruptures and is not permeable by water. 15

I claim:

1. A mine and shaft lining exposed to moisture and heavy pressure from outside, while facing the tunnel hole on the inside, said lining being composed of preshaped, yielding and water-repelling 20 bricks, consisting of tar beton.

2. A mine and shaft lining exposed to moisture and heavy pressure from outside, while facing the tunnel hole on the inside, said lining being composed of pre-shaped, yielding and water-repelling 25 bricks, consisting of tar beton of different strength, said bricks of less strength being arranged as insertions between said bricks of greater strength.

JOSEPH PARUSEL. 30
